UNITED STATES PATENT OFFICE.

HERBERT R. ROWLAND, OF EAST ORANGE, NEW JERSEY.

WELL-DRILLING ATTACHMENT.

Application filed November 4, 1921. Serial No. 512,704.

To all whom it may concern:

Be it known that I, HERBERT R. ROWLAND, a citizen of the United States, and a resident of East Orange, in the county of Essex and State of New Jersey, have invented new and useful Improvements in Well-Drilling Attachments, of which the following is a full, clear, and exact description.

10 This invention relates to improvements in well drilling attachments.

The general object of the invention is the provision of a durable and efficient device that is simple to operate to grip the casing and to retain it in any desired position.

15 A further object of the invention is the provision of means for centrally spacing the casing inside the lining.

Another object is the provision of means 20 in conjunction with the casing holding means for closing the well in case a gusher is discovered.

These and other objects of the invention will be more clearly understood from the 25 following detailed description and accompanying drawings.

Figure 1 is a vertical cross section of the preferred form of the well drilling attachment;

30 Figure 2 is a cross section along the line 2-2, Figure 1;

Figure 3 is a cross section along the line 3-3, Figure 1;

35 Figure 4 is a vertical section as shown in Figure 1 with the dog in unlocked position;

Figure 5 is a cross section along the line 5-5, Figure 1;

Figure 6 is a side elevation of a holder bar with the shell broken away;

40 Figure 7 is a perspective view of one of the joints of the adjusting ring mounted on the top shelf of the shell;

Figure 8 is a cross section along the line 8-8, Figure 1;

45 Figure 9 is a perspective view of one of the holder bars carried by the shell;

Figure 10 is a cross section along the line 10-10, Figure 9;

50 Figure 11 is a top plan view of the gripping member;

Figure 12 is a section on the line 12-12, Figure 11;

55 Figure 13 is a vertical cross section of a modification of the well drilling attachment showing a valve mounted in conjunction therewith.

Referring to the above-mentioned drawings, a well lining 15 is shown on which the well drilling attachment is mounted. This well drilling attachment consists of a curved shell 16 open at both ends like a coupling. The ends are provided with internal threads 18 and 19, the thread 19 being engaged with an external thread 20 on the lining 15. The shell is carefully designed to give the maximum necessary strength to withstand the forces exerted in the various directions by the weight of the casing or by the force applied in case a gusher is struck.

Two annular shelves 21 and 22 are made integral with the shell 16 and they extend radially inward. Two annular flanges 23 and 24 extend vertically upward from the shelf 22. This shelf is strengthened by means of web members 27 which extend between the shell 16 and the bottom of the shelf 22. A two-piece ring 25 having a groove 26 cut in its lower face is mounted on the shelf 22. The two sections of the ring are joined together by means of pins 28. Teeth 29 are provided on a section of the periphery of the ring 25 and they project radially outward. These teeth mesh with a worm 30 rotatably mounted in a chamber 31 made integral with the shell 16. The shaft 32 projects through the wall of the chamber 31 and has a handwheel 33 mounted thereon. Packing 34 is mounted about the shaft 32 so as to prevent leakage.

A plurality of holder bars 35, each conforming to the shape shown in Figures 9 and 10, are mounted to rest on the ring 25 and the shelf 21. A top elevation of these holder bars is the shape of a sector of a hollow circle while a side elevation shows them to be something of the shape of a channel bar with the exception that the lower leg forms an acute angle with the main wall while the upper leg forms an obtuse angle. As the holder bars are mounted in position their interior surfaces define the surface of a conic frustum having its smaller diameter located at the bottom. Each holder bar is provided with a depending projection 36 extending downward and with two web members 37 which join the lower leg to the wall thus adding strength. An opening 38 is provided in the wall of each holder bar and is of sufficient size to allow a dog 39, which is rotatably mounted on a rod 40 extending between the web members 37, to pass therethrough. This dog 39 is held in alignment

with the opening 38 by means of spacing tubes 41. A gripping member 42 provided with a flaring tenon 43 is mounted in a mortise 44 provided in each holder bar. When 5 mounted in position the inner face of each gripping member 42 is vertical while the outer face slopes similarly to the interior face of the holder bar. The tenon 43 of each gripping member 42 is mounted in 10 alinement with the dog 39, and a slot 45 is cut in the upper corner of the outer face of the tenon. This slot is wide enough to allow the dog 39 to fit therein. A top elevation of 15 any of the gripping members is the shape of a sector of a hollow circle. These gripping members may be made of different sizes, depending upon the diameter of the casing with which they are to be used, and it is simple to remove one set of gripping members 20 from the holder bars when it is desired to replace them by a set of different size. In conjunction with each dog 39 a set screw 46 is provided and mounted in a threaded opening 47 in the shell wall. A plurality of 25 slots 48 are provided in the upper surface of the ring 25. These slots are evenly spaced around the ring and they incline inward. The projection 36 on each holder bar is mounted in one of these slots. Plates 49, 30 which extend over the mortises 44, are attached to the holder bars by means of screws 50 and serve to prevent the gripping members from being forced out of engagement with the holder bars. Two depending lugs 35 35 51 are supplied integral with the base of each holder bar and a plate 52 is attached to each holder bar by means of screws 53 which engage with the lugs 51. This plate extends underneath the shelf 21 and serves 40 as a means for preventing each holder bar from being forced upward. A plurality of lugs 58 which extend outward are provided 45 on each holder bar and engage in grooves 59 cut in the shelf 22. These members serve to prevent lateral movement of the holder bar.

A casing 54 may be lowered through the opening in the upper end of the shell and mounted in the gripping members 42. Couplings 55 are mounted on the casing 54 to 50 serve as a means for attaching the next length of casing. The coupling above the gripping members 42 may engage with the latter to prevent downward movement, and the coupling below to prevent upward movement provided the gripping members are not tightly clamped on the casing to hold it in some desired position.

Openings 56 are provided near the base of the shell to allow the insertion of a pipe 60 in order to pump water from between the lining and casing or for the introduction of concrete or the like in order to cement the casing to the lining. These openings may be closed by plugs or any other suitable 65 means.

The shell 16 may have cast integral therewith a valve casing 60 which extends upward and has a threaded opening in its upper end, as shown in Figure 13. The valve casing has mounted therein a gate valve 61 70 of any usual construction. Web members 62 are provided for strengthening the shell 16 and the valve casing 60.

The operation of the device is as follows:

The proper sized gripping members 42 are 75 mounted in the holder bars 35, and the worm 30 is then operated by means of the handwheel 33 to rotate the ring 25 counterclockwise. As the ring rotates counterclockwise the sides of the slots 48 slide along the projections 36 integral with the holder bars 35 thus forcing the holder bars and gripping members radially outward. After the gripping members have been moved a sufficient distance radially outward the casing 54 is 80 lowered into the lining 15. When it is desired to grip the casing to hold it in order to attach another length of the casing the handwheel is operated to rotate the ring 25 clockwise thus forcing the gripping 85 members radially inward into contact with the casing 54. If there is a coupling 55 on the casing 54 it may be allowed to seat on the gripping members. Then the dogs 39 may be operated by means of set screws 46, 90 forcing them through openings 38 into contact with the gripping members, and this serves to hold the gripping members against upward movement. If the dogs 39 have not been forced inward by means of the set 95 screws 46 and an upward force is applied to the gripping members they are stopped in their upward movement by means of the plates 49. The holder bars are held in position by means of plates 52 which, in case 100 of the upward movement of the holder bars, engage the lower shelf 21. The upper end of the shell 16 has an opening therein which is provided with a thread 18 so that a pipe may be attached thereto in order to convey 105 away the contents of the well. The openings 56 in the bottom of the shell 16 are provided so that tubes may be inserted in order to remove whatever collects between the lining and the casing or in order to introduce concrete for cementing the casing to the lining. A valve casing may be made integral with the shell 16 and provided with a valve gate. This valve and valve gate 110 are provided so that the well may be closed in case a gusher is obtained. The provision of the valve in conjunction with the well drilling attachment mounted on the lining saves a great amount of work in attaching means to the casing for conveying 115 away the contents of the well.

I would state in conclusion that while the illustrated examples constitute practical embodiments of my invention I do not limit myself strictly to the exact details herein 120 125 130

illustrated since manifestly the same can be considerably varied without departing from the spirit of the invention as defined in the appended claims.

5. Claims:

1. As a new article of manufacture, an attachment for well drilling apparatus, comprising a shell for mounting on the well lining, and adjustable means for gripping 10 the well casing located in the shell.
2. In combination with a well lining an attachment for well drilling apparatus comprising a shell for mounting on the well lining, a valve carried by the upper end 15 of the shell for controlling the passage through the shell, and means located in the shell for gripping the well casing.
3. An attachment for well drilling apparatus, comprising a coupling for mounting 20 on the well lining, and adjustable means located in the coupling for holding and centering the well casing.
4. An attachment for well drilling apparatus, comprising a shell for mounting on 25 the well lining, removable gripping members mounted in the shell for holding the well casing, and means carried by the shell for operating the gripping members.
5. An attachment for well drilling apparatus, comprising a shell for mounting on 30 the well lining, gripping members located in the shell for holding the casing, and means associated with the gripping members for operating them.
- 35 6. An attachment for well drilling apparatus comprising a shell for mounting on the well lining, gripping members for gripping the well casing located in a circle in the shell, and means for moving the gripping members along radial lines to grip and release the well casing.
7. An attachment for well drilling apparatus, comprising a shell for mounting on 45 the well lining, removable gripping members mounted in the shell for gripping the well casing, means for operating the gripping members, and means for locking the gripping members in contact with the well casing.
- 40 8. An attachment for well drilling apparatus, comprising a shell for mounting on the well lining, removable gripping members mounted in the shell for gripping the well casing, means for operating the gripping members, and a valve mounted on the upper end of the shell for controlling the passage therethrough.
- 55 9. An attachment for a well drilling apparatus, comprising a shell for mounting on the well lining, a pair of annular shelves carried by the shell, a ring rotatably mounted on the upper shelf, a plurality of holder bars mounted on the ring and lower shelf, gripping members removably mounted on the 60 holder bars, means for rotating the ring, and means in conjunction with the ring and holder bars for moving the latter radially to move the gripping members radially as the ring is rotated.
10. An attachment for a well drilling apparatus comprising a shell for mounting on the well lining, a pair of annular shelves carried by the shell, a ring rotatably mounted on the upper shelf, a plurality of holder bars mounted on the ring and lower shelf, gripping members removably mounted on the holder bars, means for rotating the ring, means in conjunction with the ring and holder bars for moving the latter radially to move the gripping members radially as 75 the ring is rotated, and means for locking the gripping members in their active position.
11. As a new article of manufacture, an attachment for well drilling apparatus comprising a shell for mounting on the well lining, annular shelves carried by the shell, a ring rotatably mounted on the upper shelf, inclined slots cut in the surface of the ring, holder bars having depending projections mounted on the ring, the projections fitting in said inclined slots, gripping members mounted on the holder bars, teeth in conjunction with said ring and meshing with a worm carried by the shell, and means 80 for operating the worm to rotate the ring to move the gripping members radially.
12. As a new article of manufacture, an attachment for well drilling apparatus comprising a shell for mounting on the well lining, means located in the shell for gripping and holding the well casing, external means carried by the shell and associated with the gripping and holding means for operating the latter, and openings extending through the shell leading to the space between the well lining and well casing.
13. As a new article of manufacture, an attachment for well drilling apparatus comprising a fitting for mounting on the well lining, means for gripping and holding the well casing located in said fitting, external means supported by the casing and associated with the gripping members for operating the latter, and a valve associated with the upper end of the casing to control the passage thereof.
14. As a new article of manufacture, an attachment for well drilling apparatus, comprising a spherical coupling open at both ends for mounting on the well lining, means for gripping the well casing to hold and center the latter, means for operating the said gripping and holding means carried by the shell, and means for locking the gripping and holding means in active engagement with the casing.
15. An attachment for well drilling apparatus comprising a shell for mounting on the well lining, means for gripping and hold- 125

ing the well casing located in the lower end of the shell, means for operating the gripping and holding means carried by the shell, and a valve located in the upper end of the shell 5 to control the passage thereof.

16. An attachment for well drilling apparatus comprising a shell for mounting on the well lining, annular shelves carried by the shell and extending radially inward, a 10 ring having inclined slots cut therein rotatably mounted on the upper shelf, holder bars having depending projections for en-

gaging in said slots carried by the ring and lower shelf, gripping members having flaring projections mounted on said holder bars, 15 the flaring projections engaging in mortises provided in the holder bars, means for rotating the ring to move the gripping members radially to grip the well casing, openings leading through the shell casing into 20 the space between the well lining and the well casing, and a gate valve supported in the upper end of the casing.

HERBERT R. ROWLAND.
